Hays.

UNITED STATES PATENT OFFICE.

GEORGE A. VICKERY, OF LEXINGTON, MASSACHUSETTS.

RECEPTACLE.

1,416,914.

Specification of Letters Patent. Patented May 23, 1922.

Application filed April 16, 1921. Serial No. 461,768.

To all whom it may concern:

Be it known that I, GEORGE A. VICKERY, a citizen of the United States, and resident of Lexington, county of Middlesex, Commonwealth of Massachusetts, have invented an Improvement in Receptacles, of which the following description, in connection with the accompanying drawings, is a specification, like characters on the drawings representing like parts.

This invention relates to receptacles for liquids and particularly liquids in bottles.

Its object is to provide a receptacle where the bottled liquid, such as milk, can be quickly deposited by the delivery man and be safe from annoyance by animals, as dogs or cats, and shielded from the hot sun and weather.

In the drawings of the present embodiment of my invention,

Fig. 1 is a front view showing the stirrup and liquid container, as a bottle, in dotted lines; and

Fig. 2, a vertical section on the line 2—2, Fig. 1, and showing, in dotted lines, the stirrup and container in raised position, the latter in position to be removed.

One form of my novel receptacle is herein illustrated as comprising a cylindrical member 1, of any suitable material as metal, and having an inner wall 2 and outer wall 3 suitably lined or coated if desired with an air space or chamber 4 between them providing substantially a thermos construction. The receptacle may be carried by a base 4^a with a vertical rib 4^b for suspending it if desired, to any convenient support. The air in the chambers 4 may be exhausted if preferred, to create a vacuum.

The cover 5, Fig. 2, may be similarly constructed with corresponding inner and outer walls and such a container will protect the contents for a long time against extreme atmospheric conditions.

In order to render such a receptacle most convenient for use, I have provided the cover with a stirrup 6 for holding the container and comprising a wire bent at its center to form two legs 7, the ends of which are bent laterally to form supporting arms

8 for the container 9. The stirrup can be supported from the inside or lower face 3 of the cover by any convenient means as a screw eye 10.

In order to hold the cover in raised position after it has been raised with its container, if empty, I have provided it with a spring 11. One end of the spring is secured to the cover by a pin 12 seated in a slot 13 in the cover, and the opposite spring end 60 is secured to a pin or other anchorage 14 in the recess 15 in the rib 16 on the back of the container.

In use the cover is first raised and then the bottle is deposited on the stirrup arms 8, where the weight of the bottle will overbalance the action of the spring 11 and drop within the container and cause the cover to close automatically.

When the container is to be removed it will be raised to a position where it can be conveniently grasped, by simply raising the cover by its lift 17.

While the container, if filled, and in lower position will overbalance the spring 11 when the cover has been closed, the spring will hold the cover and its suspended container in raised position if the latter is empty.

It will be obvious that my novel container will provide a safe and convenient receptacle for bottles of milk or any liquid that it may be desired to safeguard from the sun, rain, and dogs, or even small children, by placing it at a proper height, above the ground.

My invention is not limited to the embodiment illustrated, and I claim:

1. A receptacle comprising a hollow body, a cover with a container stirrup carried thereby, a spring on the body adapted to hold the cover, stirrup and empty container in raised position, and when a full container is placed on the stirrup, to yield and permit the cover to close and container to drop into the receptacle.

2. A thermos receptacle comprising a hollow body, a cover with a container stirrup carried thereby, a spring on the body adapted to hold the cover, stirrup and empty container in raised position and when a full

100

container is placed on the stirrup, to yield and permit the cover to close and container to drop into the receptacle.

3. A thermos receptacle with a cover, and 5 having in combination therewith a container stirrup carried by the cover, a downwardly acting spring on the body tending to raise the cover stirrup and empty con-

tainer to raised position, and when a full container is placed on the stirrup to yield 10 and to permit the cover to close and the container and stirrup to drop into the receptacle.

In testimony whereof, I have signed my name to this specification.

GEORGE A. VICKERY.
